UNITED STATES PATENT OFFICE.

JOHN T. KEMPS, OF CUBA, WISCONSIN, ASSIGNOR OF ONE-THIRD TO HENRY FUSH AND ONE-THIRD TO SHERMAN E. SMALLEY, BOTH OF CUBA, WISCONSIN.

HAT-PIN-POINT-PROTECTING DEVICE.

1,193,556.

Specification of Letters Patent.

Patented Aug. 8, 1916.

Application filed August 22, 1912. Serial No. 716,509.

To all whom it may concern:

Be it known that I, JOHN T. KEMPS, a citizen of the United States, residing at Cuba city, in the county of Grant and State 5 of Wisconsin, have invented new and useful Improvements in Hat-Pin-Point-Protecting Devices, of which the following is a specification.

My invention relates to a hat pin point 10 protecting device which is designed to prevent serious accidents which are liable to occur when the points of the hat pins are left uncovered.

My invention as disclosed herein is readily 15 attachable to and detachable from the hat pin and can be easily manipulated by any inexperienced person.

An object of my invention is to provide 20 a hat pin point protector which is simple in construction, strong and durable and efficient in operation, and one which can be manufactured and placed upon the market at a minimum cost.

With the above and other objects in view, 25 my invention relates to such details of construction and in the arrangement and combination of parts as will be hereinafter fully described and specifically set forth in the appended claim.

30 In describing my invention in detail, reference will be had to the accompanying drawings wherein like characters denote like or corresponding parts throughout the several views, and in which:—

35 Figure 1 is a side elevation of my invention. Fig. 2 is a longitudinal sectional view of my invention showing the same in a locked position upon the hat pin. Fig. 3 is a longitudinal sectional view of my invention showing the same in an unlocked position upon the hat pin, and Fig. 4 is a cross sectional view taken on line $a-a$ of Fig. 2.

In the accompanying drawings wherein 45 is illustrated the preferred form of my invention, the numeral 1 designates an ordinary hat pin which has provided at one extremity thereof an ordinary head portion 2 which may have any ornamental design 50 positioned thereon as desired by the wearer thereof. The other end of the pin is sharpened as is usually the case and is received into a longitudinal opening 3 in a sleeve 4 carried by another head portion 5. The

sleeve 4 and second head portion are formed 55 integral with each other as designated, and can be constructed of any suitable material.

Means are provided upon the sleeve to grip the pin and hold the same in the opening 3. This means comprises a member 6 60 which is substantially semi-circular in cross section and which is pivoted upon, through the medium of a pintle 7, a pair of ears 8. From an inspection of Figs. 1, 2 and 3 of the drawings it will be readily seen that the 65 sides of the member 6 extend to engage the sleeve 4 and that in order to permit the member 6 to move from the position shown in Fig. 2 to the position shown in Fig. 3 this member must be formed from resilient 70 material such as sheet metal. By having the member 6 formed of resilient material a greater effort will be necessary in order to move the same from the position shown in Fig. 2 to that shown in Fig. 3 than would 75 be required if the sides of the member 6 did not engage the sleeve 4 and therefore this binding action created will serve as additional means for preventing the member from moving out of the normal position 80 shown in Fig. 2 when placed upon the pin. An elongated tongue 9 is formed integral with the member 6, and is bent downwardly at right angles thereto to extend within the slot 10 in the sleeve. The lower extremity 85 of the tongue is then introduced into an opening 11 in the pin, whereby the latter will be securely held in place. Spring 12 is provided to normally maintain the tongue 9 in engagement with the notch 11. This 90 spring, as shown, is wrapped loosely around the pintle 7 and has one end or arm bearing against the locking member 6 and the other end or arm bearing against the sleeve or head member 4. It will be noticed that this 95 spring 12 is mounted intermediate the ears 8, which ears, owing to the fact that the spring loosely surrounds the pintle, positively prevent disengagement of the spring from the pintle.

100 From the foregoing, it will be recognized that my device is very simple, it consisting of but few parts, and that the same can be manufactured and placed upon the market at a very low cost.

105 I desire to be understood that I may make slight changes in the construction and in the arrangement and combination of parts with-

out departing from the spirit of my invention, provided such changes fall within the scope of the subjoined claim.

Having thus fully described my invention, what I claim as new, and desire to secure by Letters Patent, is:—

10 A pin protector comprising a cylindrical tube provided with a side opening communicating with its longitudinally extended opening, pivot ears extending from said tube, a pawl pivotally connected with said pivot ears and provided with a gripping tongue extending through the side opening

of said tube, said pawl being formed of resilient material and provided with side 15 walls extending along the side portions of said tube in contacting relation therewith to cause a binding engagement therewith when said pawl is moved to a releasing position, and resilient means normally holding said 20 pawl in an operative position.

JOHN T. KEMPS.
